S. E. CARPENTER

INTERLOCKING SHINGLE ROOF

Filed July 23, 1923

Patented Mar. 9, 1926.

1,576,090

UNITED STATES PATENT OFFICE.

SCOTT E. CARPENTER, OF MEMPHIS, TENNESSEE.

INTERLOCKING-SHINGLE ROOF.

Application filed July 23, 1923. Serial No. 653,198.

To all whom it may concern:

Be it known that I, SCOTT E. CARPENTER, a citizen of the United States, residing at Memphis, county of Shelby, and State of Tennessee, have invented certain new and useful Improvements in Interlocking-Shingle Roofs, of which the following is a full, clear, and exact description, such as will enable anyone skilled in the art to

make and use the same.

My invention relates to a roof composed of interlocking tiles or shingles and to the method of applying the same. It has for its object, the making of a roof of shingles or tiles which are so interlocked that the ends which are not nailed, will be interlocked with the shingles beneath adjacent to where the latter are nailed, whereby the otherwise free end, that is, the lower end of the shingle or tile will be prevented from curling upward or being blown upward by the wind and a water tight roof be secured.

It has for its further object the making of a roof which can be readily and rapidly laid and which will be low in cost.

In putting shingle roofs on houses, it is the universal custom to nail shingles to nailing strips or purlins at such distance from the lower end of the shingle that the nails holding the shingle down, will be covered by the ends of the next row of shingles. Where wood shingles were used, this was ordinarily a very satisfactory proposition in that the stiffness of the wood held the shingle flat, though even in that case, if the shingle was improperly cut and laid wrong side up, there was a tendency for the shingle to curl up at the end.

When however, the composition shingle made of felt and some bituminous impregnating material with a light coating ordinarily of fine gravel or slate was introduced, the thinness and the flexibility of the shingle accentuated this tendency to curl and also allowed the action of wind blowing under the free edge of the shingle to become a much more serious one. Added to this the purlins in a great many cases were spaced apart and this spacing was often such that it became necessary to drive the nails at an excessive distance from the lower edge of the shingle, thus increasing the tendency toward trouble. It later too, became evident that the bituminous shingle could be very advantageously used over an old shingle roof and that a great saving could be

secured and a more secure roof be had by leaving on the old shingles and putting the new shingles over the same. In such cases, it was necessary to drive nails through the old shingle into the purlins below and as these purlins were spaced in many cases for a different exposure, of shingle, the question of nail location became an even more serious one.

It was self-evident therefore, that some means of holding down the lower end of the shingle must be found, if any success were to be had, especially in this latter type of roof. Many attempts have therefore been made to provide a suitable interlocking tile and in carrying these out, metal wires or strips have been placed in one corner of a shingle and the shingle laid in diamond pattern with this wire or metal strip slipped under the edges of the shingles lying beneath. Similar attempts have also been made, by slitting the edges at one corner of the shingle, and slipping these edges beneath the edges of the underlying shingle. In either case, however, it has been found expedient to use a large shingle rather than the smaller shingle formerly used and because of the nature of the locking device, these roofs have resulted in virtually a single thickness at certain points of each tile.

The introduction of the diamond pattern and method of laying these roofs has resulted in great difficulty in keeping them properly aligned and the method of interlocking used, has failed utterly to assist in so aligning them.

Further objects of my invention, are; to provide a roof having more than a single thickness at every point and generally having a triple thickness; to provide in the shape of the shingle itself, means which will assist in aligning the shingles in the roof and to provide in the shape of the interlocking members, additional means which will aid in, and in fact secure proper alignment, as well as secure the holding down of the lower edge of the shingle.

I accomplish these objects as will be more fully hereinafter set out in the drawings, specifications and claims.

In the drawings:

Fig. 1, is a surface view of a portion of a roof being laid with my improved form of shingle showing one of the shingles being slipped into place.

Fig. 2, is a section through the interlock-

ing shingles and underlying layer of old shingles and the underlying purlins taken on the line II—II of Fig. 1.

Fig. 3, is a section on the line III—III of Figs. 1 and 2, showing the interlocking shingles only.

Fig. 4, is an outline view on a reduced scale of a single shingle.

Referring now to the drawings, in which reference numerals are used to indicate the various roof members, 1, 2, 3, 4 and 5 are typical shingles. 6 is a half shingle used in starting along one end of the roof, 7 and 8 are bottom or edge starting strips 15 and 9 an underlying edge strip.

In Fig. 2, 10—10 are the roof purlins and 11, old wooden shingles which in this case, have not been removed and over which, the roof has been laid.

20 These shingles may be made of sheets of any thin flexible or moldable material suitable for roofing purposes. Ordinarily they are made of paper, asbestos, or wool felt impregnated with bitumen and coated with fine gravel or slate, or of sheet metal. They may however, be made of more rigid moldable material such as concrete, asbestos, or tile provided in forming them they be suitably distorted to provide interlocking space 25 such as will be more fully hereinafter described.

25 Preferably these shingles are longer than wide, adapted to be laid with the long dimensions up and down the roof. In such case, shoulders 1^x — 1^y , 2^x — 2^y , 3^x etc., are cut on opposite sides of each shingle. These shoulders being formed, taking for example a typical shingle (Fig. 4), on each side by cutting inwardly along the lines, a , at right angles to the sides of the shingle; thence cutting out the corners so formed along the lines b . Additional cuts are made inward at right angles to these new sides along the lines d , near the lower edge of the shingle 40 so as to leave an uncut center portion or throat 1^z , of the width approximately equal to the lengths of the two cuts a . In making these cuts it is important that all of them be made symmetrical about an up and down 45 axis and it is preferable that this axis be the up and down center line of the shingle. A shingle thus formed may be interlocked as are the shingles shown in Fig. 1. It will be seen however, by reference to Fig. 4, that if 50 additional cuts are made along the dotted lines c and e , that shingles of the shape of shingle 1, of Fig. 1, will be formed and I prefer in turning out my shingles to so make it that material lying outside of the dotted line c , of Fig. 4, or the line 1^e of Fig. 1 be 55 cut away since the corners would be material which is not held down and would have a tendency to curl. It will also be seen by referring to Fig. 4, that a cut could be 60 made along the dotted line f , instead of the

dotted line c and accomplish substantially the same result. I wish it distinctly understood therefore, that it is my purpose and intent in this description to set out some of the variations in the shape of the shingle 70 which may be made without departing from my invention. The essential points are that the shoulders X and Y be formed on the two sides of the shingle intermediate its length, that the throat 1^z be approximately 75 equal to the sum of the depths of these two notches from the sides of the shingles and that a T shaped head comprising projecting tongues V and W symmetrically disposed from each side of the throat Z be formed between the throat and the lower edge of the shingle. Whereby the lower edge of the T shaped head of the overlying shingle will extend outward and lie beneath and be held down by the adjacent underlying shingles. 80

Referring now to Fig. 1 in which the shingle 1, is being placed in position over and interlocked with adjoining shingles 2 and 3 which have preferably been placed and nailed down, 12 and 13 indicating nails, 90 the tongue 1^v is slipped under the edge 2^e of the shingle 2 and the shingle 1 is moved upward, this tongue sliding under the edge of the shingle 2, until the left hand side of the throat 1^z comes into the corner 2^x of 95 the shoulder on the right hand side of the shingle 2. The top end of the shingle is then rotated to the left, the tongue 1^w being slipped under the right hand edge 3^e of the shingle 3. This movement is continued until the right hand side of the throat 1^z and the top edge of the tongue W seats against the shoulder 3^y , at which time the shingle will occupy a position similar to that occupied by the shingles 3, 4 and 5 and will have its left hand edge practically against the right hand edge of the shingle 6, though ordinarily a space of $1/8$ to $1/4$ inch is left at these points. When in place the shingle is nailed to the under-lying purlins 10 of Fig. 100 2, as near the points 14 as can be done considering the location of the under-lying purlin. Additional shingles are placed in a similar manner; if the roof is laid from the left. The same method is followed for a roof laid from right to left, except that in such case, the shingle is rotated to the right instead of to the left. This description however, is given as an illustration of the easiest methods of laying, but may be varied according to the skill and the wishes of the individual laying the roof, it being essential only that the tongues 1^v and 1^w in the case of the shingle 1 be engaged beneath the edges 2^e and 3^e of shingle 2 and 3 and the shingle then be pulled upward to seat against the shoulders 2^x and 3^y . In starting a roof of this kind, I prefer to use a strip 9, 115 preferably of the same material which is laid with its edge flush along the lower edge 120

125 9, preferably of the same material which is laid with its edge flush along the lower edge 130

of the roof, or if desired, slightly overhanging. Over this, I put a regular starting strip 7, 8. These starting strips have shoulders 7^y and 8^x — 8^y identical in spacing with 5 that on the shingles as laid on the roof. If desired, the starting strips 7 and 8 may be replaced by individual shingles of the same width as the shingles 1, 2, 3 etc. It will be seen again by reference to Fig. 1, that the 10 nails 12, 13 through shingle 3 hold that shingle down at a point very close to the shoulders 3^x and 3^y and that when a tongue 1^w is pulled into place, it is very securely held down by the nail 13 which is closely adjacent to it. The tongue 1^v being similarly held down, the lower end of the shingle is locked against curling or otherwise raising up.

With this form of shingle, I in addition 20 secure speed of laying and accuracy of laying and alignment, since each shingle is automatically aligned when the tongues thereof come against the shoulder of the under-lying shingle and is automatically 25 spaced when the shingle is swung against the adjoining shingle on the side; or if not absolutely against it, in such close proximity to it, that the hand guided by the eye, can place it.

30 I prefer of course to make my shingles of the type shown in Fig. 1, but I wish it distinctly understood that I do not by this, intend to limit myself to that shape as hereinbefore pointed out.

35 Should these shingles be of rigid material, they would necessarily be distorted as the flexible shingles are distorted in Figs. 2 and 3, in order that the tongues V and W could be slipped under the edges of the 40 adjacent shingles.

A typical example of one of my shingles would be a shingle that was 16 inches long from the upper to the lower edge and 12 inches wide. Referring this description to 45 Fig. 1, this shingle 1 would be cut inward along the line 1^a at a point 10 inches below the top of the shingle for a distance of $1\frac{1}{2}$ inches. The cuts 1^b would then be made on each side along lines parallel to the sides of 50 the shingle for a distance of $1\frac{1}{2}$ inches. Along the bottom edge cuts 1^c would be made on each side approximately 6 inches apart upward at right angles to the bottom for a distance of $1\frac{1}{2}$ inches. Diagonal cuts 55 1^e would then be made from the ends of the cuts 1^b to the throat 1^z ; thus forming the tongues 1^v and 1^w extending outward from the throat 1^z between the throat and the lower edge of the shingle. Such a shingle 60 would have a rectangular upper portion, a lower section of less width, a restricted throat adjacent the lower edge of the shingle and laterally projecting tongues between the throat and the lower edge. The dimensions to be followed even in the shingle of

the size given would not necessarily be those given in the typical example. However, the sum of the lengths of the cuts 1^a should be equal to the width of the throat 1^z and the depth 1^e of the tongues should preferably 70 be equal to the lengths of the cuts 1^b , in order to make a pleasing appearance in the roof. It will readily be understood that if such a shingle were cut down in length, from 75 16 inches and such reductions be made entirely in the upper portion of the shingle, that the only difference would be that there would be less lap on the shingles and that if this were cut down enough, the number of 80 layers in the roof would be reduced. In other words, the length of the upper portion of the shingle may be reduced to even less than the length of the lower portion. Likewise it will be seen that the width 1^e of 85 the tongue may be reduced and similarly the length of the cuts 1^b and as has been before stated, the diagonal cut 1^e may even be run from the throat 1^z directly toward the inner ends of the cuts 1^a (as indicated by the dotted line f, in Fig. 4). It will readily 90 be seen also that various sizes of shingles may be made and that the ratio of length to width may also be varied.

Having now fully described my invention, 95 what I claim and desire to secure by Letters Patent in the United States is:—

1. A shingle having a rectangular upper portion, oppositely disposed shoulders extending inward from both sides along the lower edge of said upper section, a symmetrically disposed lower section of less width than said upper portion, a restricted throat near the lower edge thereof symmetrically disposed with reference thereto, said throat being of a width equal to the combined widths of the said shoulders, and comparatively narrow rectangular tongues extending laterally outward below said throat and forming the lower edge of said shingle, the length of said tongues being equal to their width whereby when said shingle is assembled with other shingles on a roof the ends of the said tongues of an overlying shingle for their entire depth come beneath and are adapted to be held down by 105 the underlying shingle. 110

2. A shingle having an upper portion, oppositely disposed shoulders extending inward from both sides at the lower edge of said upper section and at right angles to the center line thereof, a narrower lower section extending therefrom between parallel lines and thence cut away along diagonal lines extending inward to a restricted throat near the lower edge thereof and symmetrically disposed with reference to said center line, said throat being of a width equal to the combined widths of the said shoulders, rectangular tongues of width substantially equal to that portion of said lower section which lies between parallel lines, extending outward below said throat and forming the lower edge of said shingle whereby when said shingle is assembled in a roof with other 5 similar shingles, said rectangular tongues will be entirely covered and held down by adjacent underlying shingles.

3. A shingle having an upper portion, oppositely disposed shoulders extending inward from both sides at the lower edge of said upper section and at right angles to the center line thereof, a restricted throat near the lower edge of said shingle symmetrically disposed with reference to said center 10 line, tongues extending outward from said throat section and lying between said throat and the lower edge of said shingle, and a section lying between said throat and said upper portion cut along lines extending diagonally upward and outward from said 15 throat to lines extending downward from said upper portion parallel to the center line, at the inner edges of said shoulders.

4. A shingle having an upper portion, oppositely disposed shoulders extending inward from both sides along the lower edge of said upper section and at right angles to the center line thereof, a restricted throat near the lower edge of said shingle symmetrically disposed relative to said center line, a section lying between said throat and said upper portion cut along lines extending diagonally upward and outward from said throat to lines extending downward from said upper portion parallel to the said center line at the inner edges of said shoulders, and tongues, of a width substantially equal to the length of said parallel lines, extending outward from said throat section and lying between said throat and the lower edge of said shingle.

5. A roof composed of a plurality of simi-

lar shingles each having symmetrically disposed shoulders extending inward from the edges at right angles to the center line and 45 thence downward parallel thereto, a restricted throat adjacent the lower edge of each of the said shingles and symmetrical with the center line, and tongues, of a width substantially equal to the length of said 50 parallel portion of said shoulders, lying between said throats and the lower edges of the shingles, extending laterally from said throats, whereby when two shingles are brought adjacent to and in line with each 55 other, a rectangular pocket is formed which is adapted to receive the throat of an overlying shingle and permit the tongues thereof to be slipped beneath the edges of and to be entirely covered by the underlying 60 shingles and form an interlock therebetween.

6. A roof composed of a plurality of similar shingles each having symmetrically disposed shoulders extending inward from the edges at right angles to the center line thereof, a throat equal in width to two of said shoulders, adjacent the lower edge of each of the said shingles and symmetrical with the said center line and comparatively narrow tongues lying between said throats and the lower edges of the shingles extending laterally from said throats, whereby when two shingles are brought adjacent to and in line with each other, a pocket is formed 70 which is adapted to receive the throat of an overlying shingle and permit the tongues thereof to be slipped beneath the edges of the underlying shingles and form an interlock therebetween, the length of the said tongues being such that their entire ends 75 come beneath the under-lying shingles.

In testimony whereof I have hereunto set my name.

SCOTT E. CARPENTER.
